UNITED STATES PATENT OFFICE.

JOHN C. POLING, OF NEBRASKA CITY, NEBRASKA, ASSIGNOR OF ONE-HALF TO W. B. BANNING.

METAL-REINFORCED CONCRETE PIPE.

1,325,678.

Specification of Letters Patent. Patented Dec. 23, 1919.

Application filed June 28, 1918. Serial No. 242,439.

To all whom it may concern:

Be it known that I, JOHN C. POLING, a citizen of the United States, residing at Nebraska City, in the county of Otoe and State 5 of Nebraska, have invented certain new and useful Improvements in Metal-Reinforced Concrete Pipes, of which the following is a specification.

This invention relates to improvements 10 generally in what may be termed metal reinforced concrete or plastic pipes and more particularly blocks for forming pipes or conduits or circular tubular bodies, especially of the larger or sewer-pipe type.

15 The invention has for its object to provide for effectively protecting all metal parts against corrosion or rusting and to provide for the inexpensive manufacture of the blocks and to promote durability 20 thereof.

Other objects of the invention will be apparent as the character, advantages and uses thereof may be subsequently better understood.

25 The invention therefore consists of certain instrumentalities and features of construction substantially as hereinafter more fully set forth and defined by the appended claim.

30 In the accompanying drawings is illustrated the preferred embodiment of my invention, wherein it will be understood that various changes and modifications may be made as to the detailed construction and 35 arrangement of parts without departing from the spirit or scope of my claim, and in which drawings,

Figure 1 is a somewhat mutilated perspective view of an assemblage of blocks 40 or members for forming annular sections of a pipe, as contemplated by my invention.

Fig. 2 is a plan view of a number of assembled blocks, showing more particularly the outer and inner arrangement of the 45 constituent parts or members thereof.

Fig. 3 is a perspective view of a single block or section on an enlarged scale.

Fig. 4 is an enlarged plan view of a connection between the metallic reinforcing 50 members or bars of the blocks.

Fig. 5 is a detailed perspective view of an individual member of said reinforcing bar-joint-connection.

In carrying out my invention, I suitably

mold or form a block or section, designated 55 generally as 1, adapted to form by arranging a plurality thereof together, a pipe, especially of the larger or sewer-pipe type. The block or section 1 is arcuate or concave in its general outline or contour and, 60 in addition, is stepped at its ends, thereby forming overlapping terminals or shoulders 2 at those points to provide overlapping joints between abutting or contacting blocks. Said block is also stepped in transverse section, resulting in producing along its inner upper and lower edges, shoulders 3, and along its outer upper and lower edges, shoulders 3^a, said shoulders being adapted to form 65 overlapping joints, at said points, with correspondingly formed shoulders of adjacent blocks in the pipe-formation.

The blocks or sections are suitably assembled, block to block, to form an annular or circular disposition thereof, with their 75 end shoulders 2 interlocking, while each annular or circular arrangement of blocks is opposed end to end, breaking joints with the aforesaid blocks or sections, the concaved tenon-like shoulders 3 overlapping 80 each other, thus providing for building up or forming the pipe. The sections or blocks 1 may be assembled in any desired number, according to the diameter it may be required to impart to the prospective pipe. 85 Also the sections or blocks are interlocked and reinforced by metallic bars or members 4 and 5, positioned vertically and horizontally and embedded in the concrete of the blocks as the latter are being built up from 90 the concrete material, as seen particularly in Fig. 1, at the point of the omission of a block or section for that purpose. These reinforcing members 4 and 5 are themselves secured in position, when applying the concrete material therearound, by means of brackets or lugs 6 of general angular formation, each having a laterally projecting terminal 6^a and an oppositely projecting shoulder 6^b a short distance from said terminal; a nut equipped bolt 7 being inserted through apertures 7^a of a pair of brackets, after passing stem-terminals of said brackets through apertures 7^b in said reinforcing metallic bars, all as seen particularly in Fig. 105 4. The laterally projecting terminals 6^a and the shoulders 6^b of the pairs of brackets 6, it will be observed, fit upon opposite sides

- of the reinforcing metallic bars 5 and thus provide for clamping the brackets, without the aid of additional means, in position to said reinforcing bars.
- 5 In applying or attaching the brackets to the reinforcing and interlocking bars, they are slightly moved out of a right angled position to the reinforcing bars and in that position enabled to be passed through the 10 holes 7^b of the latter, the brackets then being adapted to be positioned, with the laterally extending terminals and shoulders of said brackets brought flat against the reinforcing bars.
- 15 It is obvious that the various joints between the parts, all being suitably filled in with concrete as conventionally indicated more particularly in Fig. 1, the same will present a water proof structure as required 20 for its intended purpose.
- It is thought that from the foregoing my invention, both as to construction and application, will be readily and fully understood.
- 25 Various changes in the form, proportions and minor details of construction may be resorted to without departing from the principles or sacrificing any of the advantages as defined in the appended claim.
- Having described my invention, what I claim as new and desire to secure by Letters Patent, is:—
- An improvement in the construction of pipes of the character described, including a block of general arcuate outline having its 35 ends formed with stepped terminals, forming shoulders thereon, said block also being transversely stepped, providing shoulders along its inner upper and lower edges and along its outer upper and lower edges, 40 said shoulders being adapted to form overlapping joints with correspondingly formed shoulders on contacting blocks in the pipe formation and interlocking means for the block comprising embedded reinforcing 45 metal members and angular brackets, each having a laterally extending terminal and an oppositely extending shoulder-forming projection spaced with respect to said terminal to receive therebetween said reinforcing 50 members and a coupling means between said angular brackets.

In testimony whereof I affix my signature.
JOHN C. POLING.
